Primary Examiner — John R Yeh

(57) **CLAIM**

The ornamental design for a hair scraper, as shown and described.

DESCRIPTION

FIG. 1 is a front, top and right-side perspective view of the hair scraper showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof; and,

FIG. 9 is a perspective view of the hair scraper shown in a position of use with environmental subject matter.

The broken lines throughout the drawing figures depict portions of the hair scraper that form no part of the claimed design.

The broken lines in FIG. 9 depict environment of the hair scraper that form no part of the claimed design.

1 Claim, 9 Drawing Sheets
